UNITED STATES PATENT OFFICE.

ADOLF FREDRIK RINGSTRÖM, JR., OF SKIEN, NORWAY.

AEROPLANE.

1,165,805.

Specification of Letters Patent. Patented Dec. 28, 1915.

Application filed August 9, 1915. Serial No. 44,628.

To all whom it may concern:

Be it known that I, ADOLF FREDRIK RINGSTRÖM, Jr., a subject of the King of Norway, residing in the town of Skien, Norway, have 5 invented certain new and useful Improvements in Aeroplanes, of which the following is a specification.

My invention relates to improvements in aeroplanes the object being to devise means 10 by which the machine is maintained in horizontal position during downfall by accident and not by being steered by the horizontal rudder.

On the appended drawing an aeroplane 15 provided with my improved device is shown in Figure 1 in elevation and in Fig. 2 in front view.

The machine is provided with the side-planes *a*, which are stayed by braces *b*, *c*, *d*, 20 *e* in the ordinary manner.

f and *g* are the the horizontal rudders; *h* is the vertical rudder; *j* is the propeller-shaft with propeller *k*; *l* is the gondola; 25 *m* and *n* are the supporting wheels, *o* and *p* are uprights or posts forming part of the frame of the machine.

According to my invention the center-

portion of the frame of the machine is built with longitudinal bars *q* and *r* forming a kind of skeleton for a strip of cloth *s*, which 30 is wound around the said skeleton with comparatively wide openings between the turns.

The effect of the above described device is that the pressure exerted by the air on 35 the underside of the top surfaces above the said openings will tend to maintain the spiral in a horizontal position during accidental downfall of the machine.

If the walls of the cylinder were closed, 40 during a downfall of the machine the tendency would be to place the machine in a vertical position.

What I claim is:—

In aeroplanes the arrangement of a skele- 45 ton cylinder along the horizontal axis of the machine and a strip of cloth or the like wound around the said skeleton with com- paratively wide openings between the turns 50 for the purpose specified.

In testimony whereof I affix my signature in presence of two witnesses.

ADOLF FREDRIK RINGSTRÖM, JR.
